UNITED STATES PATENT OFFICE.

WILLIAM H. COCHRAN, OF SPARTANBURG, SOUTH CAROLINA.

DESIGN FOR A FLOWERPOT.

Application filed July 3, 1922. Serial No. 2,932. Term of patent 3½ years.

To all whom it may concern:

Be it known that I, WILLIAM H. COCHRAN, a citizen of the United States, residing at Spartanburg, in the county of Spartanburg and State of South Carolina, have invented a new, original, and ornamental Design for Flowerpots, of which the following is a specification, reference being had to the accompanying drawing, forming part thereof.

The figure is a perspective view of a flower pot, showing my new design.

I claim:

The ornamental design for a flowerpot, as shown.

WILLIAM H. COCHRAN.
